UNITED STATES PATENT OFFICE.

RALPH SHURTLEFF, OF ST. LOUIS, MISSOURI.

FLUE-STOP.

1,314,222.

Specification of Letters Patent. Patented Aug. 26, 1919.

Application filed October 21, 1914, Serial No. 867,770. Renewed January 29, 1919. Serial No. 273,889.

To all whom it may concern:

Be it known that I, RALPH SHURTLEFF, a citizen of the United States of America, a resident of the city of St. Louis, State of Missouri, have invented certain new and useful Improvements in Flue-Stops, of which the following is a full, clear, and exact description, reference being had to the accompanying drawings, forming a part of this specification.

My invention relates to improvements in flue stops, the object being to provide a simple and inexpensive flue stop including an anchor adapted to be securely held in a flue opening and a closure positively connected to said anchor. In the preferred form of my invention, the anchor is a yieldable member adapted to be inserted into an ordinary stove pipe receiver and adapted to be anchored onto the flue structure. The closure, seated around the stove pipe opening, is connected to the anchor by an adjustable device which may be operated with the result of firmly forcing the yieldable anchor onto the flue structure, and at the same time forcing the closure onto its seat. The anchor, connected to the closure, serves as means for retaining the latter in firm engagement with its seat, and since the anchor is securely held in the flue structure, the device is well adapted to resist the pressure of air currents in the flue.

Figure I is a vertical section of a flue provided with a flue stop embodying the features of my invention.

Fig. II is a detail view of the flue stop, showing the inner face of the closure and the anchor connected to said closure.

To illustrate the practical use of my flue stop, I have shown a flue A having a stove pipe opening, and a stove pipe receiver B arranged in said opening. A closure-anchor C arranged partly within the stove pipe receiver is preferably, but not essentially, a single piece of strap iron bent to, approximately, the shape of a letter M, said anchor being provided with legs 1 having outturned feet 2 which engage the inner face of a flue wall. The legs 1 are preferably integrally connected to a bow 3 which extends across the opening in the flue wall. It will be noted that the anchor is a yieldable device which may be readily inserted into an ordinary stove pipe opening, and when it is arranged as shown in Fig. I, the anchor cannot be withdrawn without moving one of the yield-

able legs toward the other. To positively prevent an accidental movement of this kind, I preferably bend the feet 2 as shown in Fig. I so that the ends of said feet will firmly grip the flue structure when the device is in service.

A circular closure 4, seated around the flue opening, is provided with a central perforation for the reception of a connecting screw 5, the latter being screwed into the middle portion of the bow 3.

In applying the flue stop to a flue, the first step is to insert the yieldable anchor into the flue opening, and since the yieldable legs 1 tend to spring away from each other, the anchor is primarily held in position by frictional engagement with the flue structure. The screw, passing through the closure 4, is then screwed into the bow 3, and by operating this screw the angular feet 2 are moved into engagement with the inner face of the flue wall thereafter; the legs 1 are positively forced into engagement with the member B in response to the pulling action at the middle portion of the bow, and the marginal portion of the closure is firmly forced onto its seat. The yieldable anchor is thus adjusted to a position from which it will not yield in response to pressure on the inner face of the closure, the bow 3 being so arranged that such pressure will only tend to force the anchor into engagement with the flue structure.

I claim:

1. The combination with a stove pipe opening closure, of a flexible anchor back of said closure adapted to extend through said opening to a flue, the said anchor comprising a pair of parallel gripping legs adapted to contact with the wall of the opening and having feet at their inner ends adapted to bear against the flue wall, and a yieldable V-shaped spreader connection uniting the outer ends of said gripping legs and having its apex farthest from and opposite the center of said closure, and a pull connection between the center of said closure and the apex of said yieldable spreader connection, said pull connection being operable to bend said yieldable V-shaped spreader connection, thereby firmly forcing the connected gripping legs into frictional engagement with the wall of said opening.

2. The combination with a stove pipe opening closure, of a flexible anchor back of said closure adapted to extend through said

opening to a flue, the said anchor comprising a pair of parallel gripping legs adapted to contact with the wall of the opening throughout their lengths and having angular feet at their inner ends adapted to bear against the flue wall, the said feet extending backwardly at acute angles to said gripping legs, and a yieldable V-shaped spread connection uniting the outer ends of said gripping legs and having its apex farthest from and opposite the center of said closure, and a pull connection between the center of said

closure and the apex of said yieldable spreader connection, said pull connection being operable to force the angular feet into engagement with said flue wall and to thereafter bend said yieldable V-shaped spreader connection so as to firmly force said gripping legs into engagement with the wall of the stove pipe opening.

RALPH SHURTLEFF.
